UNITED STATES PATENT OFFICE.

STANLEY RICHARDS, OF DORCHESTER, MASSACHUSETTS.

RADIOCABINET.

Application filed May 25, 1928. Serial No. 280,457.

This invention relates to an improved radio cabinet which is characterized principally by a hingedly mounted lid having the complete radio receiving set suspended from its under side so that it may be swung up to expose the dial or to permit the repairs to be made or swung down from a closed position to conceal it within the main body of the cabinet.

10 More specifically speaking the improved cabinet embodies a hingedly mounted cover or lid, which in turn carries on its under side a hingedly mounted especially constructed box in which the radio receiving set is removably placed, this box having an open frame like front to expose the tuning dial, rheostat control, etc.

Other details and improvements will become more readily apparent from the following description and drawings.

In the drawings:

Figure 1 is a front elevation of a cabinet constructed in accordance with the present invention showing the lid swung up to expose the radio set for tuning.

Figure 2 is an end view of Figure 1, looking in a direction from left to right.

Figure 3 is a sectional view facing upon Figure 2 and showing the ejecting frame and stay hooks.

Figure 4 is a perspective view of the receiving set box, removed.

Referring now to the drawings by reference numerals, it will be observed that the cabinet proper is designated by the numeral 5. This cabinet may be of any suitable design and construction. It will preferably have a built in loud speaker and will be constructed to accommodate the battery, wires, etc.

As before intimated, it is provided with a lid or cover section 6, hingedly mounted as at 7, to the body of the cabinet. Suspended from the under side of this lid is a suitably shaped box or container 8. As shown in Figure 4, the box has an open frame like front 9 to expose the dials of the radio receiving set 10. It is open on its bottom and has a central bracing strip 11 extending across the bottom. In addition, it is provided with a cross piece 12, equipped on its under side with brackets 13. These brackets 13 cooperate with similar brackets 14 on a cleat 15, attached to the inside of the cabinet as shown in Figure 3. These brack-

ets are constructed to accommodate expansion coiled springs 15, which function to normally move the cover, box and radio receiving set to upwardly inclined position as shown in the drawings. It will be noted 60 that I provide one or more stay hooks 17, engageable with eye 18, to steady the cover when it is in raised position.

It is to be observed too, that the cover is provided with headed studs 19, with which 65 pivotally mounted latches 20 cooperate. In addition, the box 8 is hingedly mounted, as at 21, on the under side of the cover. This hinged mounting of the box permits easy 70 insertion and removal of the radio receiving set for repairs. The open bottom of the box prevents entangling of the wires and permits proper assembling of the conductor. The latches and cooperating headed studs serve to hold the box in suspended position. 75 The open front of the box permits access to be had to the dials for tuning. The spring serves to automatically raise the cover, box and radio receiving set and the stay hooks permit the same to be arranged 80 and held in a set position as is evident from the drawings.

It is apparent from the foregoing description and drawings that I have evolved and produced a novel character of radio cabinet 85 efficient in performance, capable of fulfilling the requirements of a device of this class, positive and dependable in operation, smooth and quiet in operation, and a novel contribution to this art. It is characterized by 90 a novel organization of parts which serve to render it practicable and especially suitable for the purposes intended. It is thought, however that a careful consideration of the description and drawings will enable persons skilled in the art to which the invention relates to obtain a clear understanding of the same. Therefore a more lengthy description is regarded as unnecessary.

100 Minor changes in the shape, size, and rearrangement of parts coming within the field of invention claimed may be resorted to, if desired.

I claim:

1. In a cabinet of the class described embodying a hingedly mounted cover, a container for a radio receiving set suspended from the under side of the cover and movable in and out of the cabinet, said container 110

being in the form of a box shaped to receive the radio set, and said container being provided with an open frame like front to expose the operating appliances on the receiving set.

2. In a cabinet of the class described embodying a hingedly mounted cover, a hingedly mounted open bottom box carried by the under side of the cover and movable in and out of said cabinet, retaining means for

fastening the box to the cover, an open frame-like front formed on the box to expose the dial and appliances on the panel of the set, spring means associated with the cabinet and box to automatically move the cover to a raised position, and a stay device associated with the cabinet and box.

In testimony whereof I affix my signature.

STANLEY RICHARDS.
